US0D1026896S

(12) **United States Design Patent** (10) **Patent No.:** **US D1,026,896 S**
(45) **Date of Patent:** **** May 14, 2024**

(54) **INFORMATION HANDLING SYSTEM**

(71) Applicant: **Dell Products L.P.**, Round Rock, TX (US)

(72) Inventors: **Yuan-Ping Chu**, North District (TW); **Cecilia Hsiao Sun**, Austin, TX (US); **Paul J. Doczy**, Austin, TX (US)

(73) Assignee: **Dell Products L.P.**, Round Rock, TX (US)

(**) Term: **15 Years**

(21) Appl. No.: **29/834,438**

(22) Filed: **Apr. 12, 2022**

(51) LOC (14) Cl. **14-02**

(52) U.S. Cl.

USPC **D14/314**

(58) **Field of Classification Search**

USPC D14/140.2, 300–302, 308–312, 314, D14/348–359, 444–446, 450; D13/103, D13/110, 112, 122, 158–160, 184; D21/324, 515, 499

CPC G11B 33/02; G11B 33/128; G06F 1/20

CLAIM

We claim the ornamental design for an information handling system, as shown and described.

DESCRIPTION

FIG. 1 is a top front perspective view of the information handling system, showing the new design;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof; and,

FIG. 8 is a bottom rear perspective view thereof.

Broken lines shown in the drawings illustrate portions of the information handling system and form no part of the claimed design.

1 Claim, 6 Drawing Sheets
